COAXIAL TRANSMISSION LINE

William A. Bruno, Astoria, Long Island, N. Y., assignor to the firm Bruno Patents Inc., Long Island City, N. Y.

Application August 27, 1942, Serial No. 456,317

2 Claims. (Cl. 285—111)

This invention relates to transmission lines of co-axial electrical conductors, and has particular relation to joints between sections of co-axial conductors, in which one conductor is concentrically located inside of the other. It is particularly useful for interconnecting sections of ultra-high frequency co-axial conductors.

The main object of this invention is to provide an improved method and means for properly connecting the tubular outer conductor sections of co-axial transmission lines, as well as the inner conductor sections located inside of said outer conductor sections.

Another object of this invention is to provide a co-axial transmission line which may be of relatively great length, and in which the outer conductor sections and inner conductor sections can be easily assembled in the desired positions.

A further object of the invention is to provide an improved method and means for connecting outer and inner conductors of relatively short conductor sections forming an angle with the main conductor line to the outer and inner conductors of the latter.

Other objects and advantages will appear to those skilled in the art from the following specification and claims, and the appended drawings which illustrate, by way of example, some preferred embodiment of the invention, and in which

Figures 1a and 1b represent a diagrammatic illustration of a joint formed between two outer conductor sections according to my invention;

Figures 2a, 2b and 2c illustrate diagrammatically a T-shaped co-axial conductor line, in which the horizontal conductor comprises sections joined together according to the invention;

Figures 3a, 3b and 3c illustrate a preferred embodiment of a T-shaped central conductor joint;

Figures 4a and 4b illustrate diagrammatically a transmission line comprising several outer conductor sections joined according to this invention, said lines being supported by stubs comprising outer and inner conductors, and

Figures 5a, 5b and 5c show in detail the T-shaped joint of the transmission line illustrated in Figs. 4a and 4b, and the cap used therein.

Referring now particularly to Figs. 1a and 1b, 1 and 2 are outer co-axial cable sections having equal, uniform, circular interior cross-sections and being adapted to house co-axially arranged inner conductors (not shown in these figures). In order to connect sections 1 and 2, a V-shaped incision 3 is made in conductor section 1. The

sides 3', 3' of incision 3 form in the drawings an angle, the vertex of which lies in a central, axial line of cable section 1. This angle may be a right angle, as shown in the drawings, or an acute or obtuse angle. I prefer the use of an incision corresponding to a right angle. At the end surface of conductor section 1, said incision has a width equal to the diameter of the conductor. Conductor section 2 is provided with a V-shaped end registering with V-shaped incision 3, and conductor sections 1 and 2 may be connected by soldering or welding conductor section 1 at its V-shaped incision to the V-shaped end of section 2, as shown in Fig. 1b.

In carrying out this invention, a conductor section 2' may be used, which is provided with a V-shaped incision 5. The sides 5', 5' of this incision form in the drawings a right angle, the vertex of which lies in a central, axial line of conductor section 2'. In assembling the transmission line, conductor sections 1' and 2' may be connected as explained above, and a central conductor 6 is now introduced into the connected outer conductor section 1' and 2'. A second central conductor section 6' is now introduced into conductor 2' through incision 5, and connected with central conductor 6 by soldering or welding, as shown in Fig. 2b. Central conductor section 6' is now introduced into an outer conductor section 7, which is provided with a V-shaped end 8, registering with V-shaped incision 5, and outer conductor section 7 is connected by soldering or welding conductor section 2' at its V-shaped incision 5 to the V-shaped end of conductor section 7, as shown in Fig. 2c.

In proceeding in the above described manner, conductor sections 1 and 2 may be easily and accurately assembled and connected, and yield a smooth, substantially unbroken cylindrical conducting surface. Furthermore, connection of central conductor sections 6 and 6' can be conveniently made through incision 5. The transmission line of the type shown can be easily manufactured and its parts can be assembled to a unit, the parts of which are arranged exactly in their desired position.

Central conductor section 6 and 6' have substantially equal, uniform, circular outside cross-sections, and they may be tubular elements or preferably solid rods. In assembling the parts shown in Figs. 2a, 2b and 2c in the above described manner, connection of central conductor sections 6 and 6' may be effected in a manner similar to that above described with reference to outer conductor sections 2' and 7. Thus,

a V-shaped incision 9 is provided in central conductor section 6, the sides of said incision forming in the drawings a right angle, the vertex of which lies in an axial, central line of conductor section 6. Central conductor section 6' is provided with a V-shaped end 9' registering with incision 9. Conductor section 6 is then soldered or welded at its V-shaped incision 9 to V-shaped end 9' of conductor section 9'.

In the preferred embodiment shown in Figs. 3a-3c, a sleeve 31 is slid over central conductor 6. Said sleeve is provided with an orifice 32 and is soldered to conductor 6 at 33 and 33'. Conductor section 6' has an end portion 34, registering with orifice 32, and conductor section 6' may be soldered to sleeve 31 at the periphery of orifice 32. The T-shaped conductor comprising conductor sections 6 and 6' may be assembled with corresponding outer conductor sections substantially in the manner explained above in connection with Figs. 2a-2c.

The co-axial transmission line shown in Figures 4a and 4b comprises several axially aligned outer conductor sections which are connected with each other by soldering at their V-shaped incisions 3 and the adjacent registering V-shaped ends 4, according to this invention. A centrally positioned, co-axial inner conductor 16, which consists of a relatively long rod or tube, is housed by outer conductor sections 11. The transmission line illustrated in these figures, comprises supporting stubs which consist of outer conductor sections 12, each of which is provided with a cap 14 having as an integral part a central conductor element 15, said elements 15 being provided at their end with a thread 17 and adapted to be screwed into registering elements 18 of central conductor 16. Cap 14 has two edges 41, at which it may be engaged by a tool in order to screw element 15 into part 18.

As shown in Fig. 5a, sleeve 31 is slid over central conductor 16, and is soldered to conductor 16 at 33, 33'. Element 18 which is provided with a threaded bore, is soldered to sleeve 31 at the periphery of orifice 32, and is adapted to receive the threaded end portion of central conductor element 15.

In order to assemble the transmission line shown in Fig. 4a, the individual outer conductor sections 11 are first provided with V-shaped incisions 3 and registering V-shaped ends 4, and

also with V-shaped right angle incisions 25. The registering V-shaped ends of outer conductor sections 12 are then connected with individual conductor sections 11 by soldering at incision 25. Sections 11 are then connected with each other by soldering, as described above.

Sleeves 31 are slid over central conductor 16, and are soldered to conductor 16 at 33, 33'. Elements 18 are connected to sleeves 31 by soldering. These elements are so dimensioned that assembled rod 16 can be conveniently introduced into the connected outer conductor sections 11.

After introducing central conductor 16 into outer conductor 11, caps 14 are applied to outer conductor sections 12 and inner conductor sections 15 are connected with elements 18 by screwing, as shown in Fig. 5a. Finally, caps 14 are connected to conductor sections 12 by soldering at 27.

It will be understood that this invention may be carried out in other specific ways than those herein set forth, and the embodiments should be, therefore, considered as illustrative and not restrictive within the spirit of the invention as defined in the appended claims.

I claim:

1. A co-axial, electrical transmission line comprising a first tubular conductor section provided at its end with a longitudinally arranged V-shaped incision, the sides of which lie in planes, a second tubular conductor section having an inner diameter equal to that of said first section, and a V-shaped end portion registering with said V-shaped incision, said second section being connected to said first section by soldering or welding at said V-shaped incision.

2. A co-axial, electrical transmission line comprising a first tubular outer conductor section provided at its end with a longitudinally arranged

V-shaped incision having at the end surface of said section a width equal to the diameter of the section, the sides of said incision lying in planes forming a right angle, the intersection line of said planes lying in a central axial plane of the conductor section, a second tubular outer conductor section having an inner diameter equal to that of said first section, and a V-shaped end registering with said V-shaped incision, said section being connected to said first section by soldering or welding at said V-shaped incision.

WILLIAM A. BRUNO.
